TWO-CYCLE ENGINE.

1,114,272.

Specification of Letters Patent.

Patented Oct. 20, 1914.

Application filed November 12, 1913. Serial No. 800,477.

To all whom it may concern:

Be it known that I, KARL KUTZBACH, a subject of the King of Saxony, and residing at No. 24 Liebigstrasse, Dresden, in the Kingdom of Saxony and the German Empire, have invented new and useful Improvements in Two-Cycle Engines, of which the following is a specification.

My invention relates more especially to double-acting two-cycle engines provided with scavenging and exhaust slots so arranged that after the closing of the exhaust slots compressed air is forced through the scavenging slots into the cylinder. The scavenging slots are preferably arranged in two parallel rows and so positioned that the exhaust slots extending in the axial direction of the cylinder lie between them. The two rows of these scavenging slots are controlled by a valve in such a way that as the piston moves forward the row of scavenging slots first uncovered by the piston still remains closed so that no compressed air can enter through these scavenging slots. When on the further forward movement of the piston the exhaust slots are uncovered and the exhaust of the gases begins, the second row of scavenging slots is also uncovered and the scavenging of the cylinder now begins. Upon the reversal of the movement of the piston also the previously uncovered but still closed row of scavenging slots is opened, and as these slots are covered again by the piston, later than the exhaust slots, compressed air can continue to flow into the cylinder, even after the exhaust slots have been closed.

In the accompanying drawing Figure 1 is a central longitudinal section through one end of a jacketed engine cylinder and a section through a portion of the air supply pipe showing the arrangement of the valve; Fig. 2 is a section through a portion of the air supply pipe showing a different kind of valve.

a is the cylinder jacket, *b* the piston, and *c* are the exhaust slots extending in the axial direction of the cylinder.

The two rows of scavenging slots are marked *d* and *f* respectively, and they are connected with a pipe *g*, through which compressed air may be supplied to said scavenging slots. At the junction of the said pipe and the passages leading to the scavenging slots a controlling member is provided

which, according to Fig. 1 of the drawing, consists of a rotary valve *i* and controls the supply of compressed air to both rows *d* and *f*. The corresponding positions of the valve *i* and the piston *b* are indicated by marking the center lines of these elements with the same Roman figures, I, II, III, IV.

The operation is as follows: When the piston *b* moves from the left in Fig. 1 to the right and approaches the dead center position, the scavenging slots *d* have just been uncovered. At this moment, however, they are still closed against the pipe *g* by the valve *i*, as seen in Fig. 1. During the further movement of the piston toward the right, the exhaust slots *c* are opened and the exhaust begins. Thereupon also the scavenging slots *f* are uncovered, and as these slots are open toward the pipe *g* compressed air can enter through the slots *f* into the cylinder. When the piston *b* has reached its dead center position, as shown in Fig. 1, the valve *i* is moved to gradually open the slots *d*. During the return movement of the piston from the right in Fig. 1 toward the left, the cylinder is scavenged by the compressed air entering through the slots *f*, and when these slots are covered by the moving piston *b* the scavenging is continued by the compressed air entering through the slots *d*. As the piston moves farther toward the left and approaches its other dead center position indicated by the broken line marked by the Roman figure III, then the scavenging of the cylinder begins at the opposite end of the cylinder in a similar way as when the cylinder moved from the left in Fig. 1 toward the right. In this case, however, the slots *f* are first uncovered by the piston but are still closed against the pipe *g* by the valve *i* which by that time has reached the position opposite to that shown in Fig. 1. As the piston moves farther toward the left of Fig. 1 the exhaust slots *c* are opened and the exhaust begins, and after the piston has uncovered the slots *d* compressed air will flow into the cylinder through these slots. When the piston *b* has reached its left side dead center position the valve *i* has moved to a position where also the slots *f* are opened toward the pipe *g* through which compressed air

continues to flow while the piston *b* moves again from the left in Fig. 1 toward the right. Thus it will be seen that the two rows of scavenging slots *d* and *f* exchange 5 their functions in relation to the two ends of the cylinder, inasmuch as during the movement of the piston in one direction compressed air first enters into the cylinder through the scavenging slots *f* and continues 10 to flow into the cylinder through the scavenging slots *d*, and vice versa. In the practical application the valve *i*, of course, will have a slight lead over the piston, so that when the piston has reached its dead 15 center position, the slots *d* and *f* respectively are already open toward the pipe *g* so that compressed air can begin to flow through said slots into the cylinder.

In Fig. 2, a slight modification is shown, 20 inasmuch as in lieu of the rotary valve *i*, a piston valve *s* is used, but the operation is the same as the one above described.

I claim as my invention:

In a double-acting two-cycle engine the combination with the engine cylinder provided with two rows of scavenging slots, and exhaust slots, of a pipe adapted to supply compressed air to said rows of scavenging slots, and a valve arranged at the junction of said pipe and the passages leading 25 to said two rows of scavenging slots so as to control the supply of compressed air to said slots in such timed relation to the movements of the piston that the scavenging of the cylinder is always begun through one 30 row of slots and continued through the other row of slots for each side of the cylinder.

In testimony whereof I affix my signature in presence of two witnesses.

KARL KUTZBACH.
